(57) **CLAIM**

The ornamental design for a push filter with floating key lock, as shown and described.

DESCRIPTION

FIG. 1 is the front perspective view of the push filter with floating key lock according to the present invention;

FIG. 2 is the front view of the push filter with floating key lock of FIG. 1 according to the present invention;

FIG. 3 is the left side view of the push filter with floating key lock of FIG. 1 according to the present invention;

FIG. 4 is the right side view of the push filter with floating key lock of FIG. 1 according to the present invention;

FIG. 5 is the backside view of the push filter with floating key lock of FIG. 1 according to the present invention; and

FIG. 6 is the top view of the push filter with floating key lock of FIG. 1 according to the present invention; and,

FIG. 7 is the bottom view of the push filter with floating key lock of FIG. 1 according to the present invention.
